MATTRESS BORDER FORMING DEVICE

Gilbert Olson, Minneapolis, Minn., assignor to
 The Land-O-Nod Company, Minneapolis,
 Minn., a corporation of Minnesota

Application September 18, 1939, Serial No. 295,535

6 Claims. (Cl. 154—29)

My invention relates to a device for forming a mattress border wherein it is desired to provide a strong reinforced border at a minimum of cost.

Mattress borders have usually been formed of a pair of spaced sheets of cloth, having sandwiched therebetween a filling of cotton padding or the like. The inner and outer coverings have usually been stitched or riveted together at intervals to provide a reinforced wall which will maintain its shape throughout a long period of use.

It is a purpose of the present invention to form a mattress border or boxing in which a single sheet of covering cloth is folded over the longitudinal edges of a thickness of padding material and in which the seam is positioned between the edges of the border or boxing and is concealed by means of the outer border covering. In this construction the padding is confined by the folded edges of the covering and is held firmly enclosed within the covering by rows of stitching extending through the coverings and the padding.

It is an object of the present invention to provide a mattress border formed of a thickness of padding having a single sheet of casing material folded over the longitudinal edges of the same and to provide a reinforced edge on the casing material to assure the enclosure of the padding within the mattress wall. This reinforced closure is formed by folding back the marginal edges of the casing material to provide a double thickness of the casing material at the seam between the longitudinal edges of the material to ascertain that the edges of the casing material will be securely anchored within the mattress wall. This construction thus definitely confines the material within the mattress border and insures a permanent enclosure for the padding within the mattress wall.

It is the purpose of my invention to provide a guide for the padding material to direct this material to overlie the center of a sheet of casing material; and then to fold the casing material over the longitudinal edges of the padding to enclose the same. It is a further feature of a preferred form of my invention to fold back the marginal edges of the padding by a suitable guide means and to apply an outer covering member over the folded marginal longitudinal edges of the casing material so that the seam will be securely bound to permanently enclose the padding material.

It is a further feature of my invention that the 55 border of the type formed on my device.

border unit including the padding with the casing wrapped about the longitudinal edges thereof and the outer border covering material overlying the casing seam may be introduced to stitching means which will secure the opposed sides of the assembly along parallel rows of stitches or may be introduced to stitching means which will stitch the mattress border along wavy lines to form a desired decorative pattern on the border.

It is a further feature of my invention to apply a certain amount of tension upon the casing material so that this material must be drawn forcibly through the machine, thus keeping the casing material taut as it passes through the machine. In this way the casing material may be more easily folded and the folding back of the marginal edges of the casing material may be facilitated.

It is an added feature of my invention that in one preferred form of my device the casing material is overlapped along its connecting edges so that the seam need not be covered by the outer covering member as described. It is also readily possible to secure the outer covering strip on the side of the border opposite the casing seam, so that the outwardly folded marginal edges of the casing may be secured to the inner lining of the mattress extending over the spring unit. In this way the casing may be secured to the inner mattress lining on one side of the mattress border while the outer mattress covering may be secured to the border covering strip secured to the outer surface of the border.

These and other objects and novel features of my invention will be more clearly and fully set forth in the following specification and claims.

In the drawings forming a part of my specification:

Figure 1 is a side elevation view of my device for forming a mattress border.

Figure 2 is a top plan view of the device illustrated in Figure 1.

Figure 3 is a cross-sectional view in enlarged scale on the line 3—3 of Figure 2, illustrating the construction of the guides.

Figure 4 is a cross-sectional view in enlarged scale on the line 4—4 of Figure 2.

Figure 5 is a cross-sectional view of the border construction formed by the forming device.

Figure 6 is an enlarged portion of the section shown in Figure 5.

Figure 7 illustrates a mattress employing a border of the type formed on my device.

Figure 8 is a side elevation view of an alternate type of border forming device.

Figure 9 is a top plan view of the forming device illustrated in Figure 8.

Figure 10 is a cross-sectional view through the border formed in the device illustrated in Figures 8 and 9.

Figure 11 is a view similar to Figure 4, showing the device arranged to overlap the folded marginal casing edges.

Figure 12 is a cross-sectional view through a mattress border constructed on the machine formed as in Figure 11.

Figure 13 is a section through a mattress having a border constructed as illustrated in Figure 12.

The invention discloses a device for forming a mattress wall in readiness for use upon the edge of a mattress. The device comprises a frame 10 having mounted thereupon a bracket arm 11 supporting a series of parallel spaced rods or rollers 12. The sheet 13 of casing material extends from the supply pile or roll 14 and passes over the center roller 12, beneath the lower-most roller or rod 12, and over the upper-most roller 12. Movement of the casing material 13, over the various rods or rollers 12, imparts a retarding action to the cloth, the movement of the cloth by the bars or rollers creating enough friction to retard movement of the cloth through the device.

The casing material passes beneath a guiding trough 15 having opposed curved side edges 16 and a flat bottom portion 17. This trough is curved upwardly at the extreme end 19 so as to curve the cloth casing sheet 13 smoothly beneath the same. The side edges of the cloth sheet 13 are bent inwardly about the opposed curved edges 16 of the guide 15 by means of a second guide 20 enclosing the outlet end of the guide 15 and being spaced therefrom.

The guide 15 is supported as best illustrated in Figure 4 of the drawings. As will be noted in Figure 2, the guide 15 is provided with supporting portions 21 which connect the opposed sides of the curved edge portions 16 of the guide 15. Bolts 22 and 23 extend through the cross members 21 and adjustably hold the guide 15 suspended beneath substantially U-shaped frame members 24 and 25 respectively. As will be noted from Figure 4 of the drawings, the frame member 25 has a transversely extending top member 26 and legs 27 secured to the table top 29 of the frame 10 by bolts such as 30. The frame 24 is formed in a manner similar to the frame 25.

In Figure 4 of the drawings, it will be noted that the bolt 23 suspends the transversely extending connecting member 21 at a considerable distance below the cross member 26 of the frame 25. A cross member 31 connects the supporting legs 27 of each frame 24 or 25, and the outer guide channel 20 rests upon and is secured to the cross member 31 by any suitable means such as the bolts 32. The channel guides 15 and 20 are supported in spaced relationship so that the casing sheet 13 may extend between these spaced guides.

It will be understood that the sheet 13 has a natural tendency to remain flat as it leaves the tension applying rods 12 and therefore the marginal edges 33 remain flat as the casing material is folded. The shape of the casing is defined by the spaced guides 15 and 20, the guide 15 providing a mandrel about which the casing 13 may be folded, and the curved marginal edges 34 of the guide 20 acting as folding horns to fold

the casing material inwardly about the inner guide 15. The outer guide is provided with an inclined or beveled edge 35 which acts to gradually urge the casing sheet 13 upwardly and inwardly about the inner guide. As the casing sheet 13 is wider than the guide 15, the marginal edges 33 fold back over the inwardly extending guide flanges 34 on the guide 20. The casing material is thus formed into substantially a tubular casing which is relatively wide and not extremely high, with the longitudinal edges of the casing folded back upon itself to form a reinforced marginal casing edge.

A wide and relatively thin strip of padding material 36 is wound in a roll 37, placed upon a supporting shaft 39 on an upwardly extending bracket 40, forming a part of the frame 10. The padding strip 39 is pulled from the roll 37 to rest upon the inner surface of the guide channel 15. The strip 36 contacts the channel 15 adjacent the upwardly curved end 19 of the same and enters the channel 15 before the casing material has been folded sufficiently to prohibit entrance of the padding between the longitudinal edges of the casing.

A strip of border finishing material 41 is drawn from the roll 42 supported upon a bracket 43 on the supporting bracket 40, is drawn through a guide 44 to overlie the surface of the casing and padding after the casing has been folded about the padding. Both the guide 15 and the guide 20 terminate at a point spaced from the U-shaped frame 25 after the casing material has been folded about the padding strip 36. The covering or finishing border strip 41 is then drawn from the roll 42 to overlie the seam between the folded edges of the casing strip 13, and the entire assembly passes between guide rolls 45. A pair of feed rolls 46 are positioned in spaced relation to the guide rolls 45 and a series of stitching heads 47 sew a series of parallel lines of stitching through the assembled unit. The rows of stitching pass through the border covering member, the casing material, and the padding to provide a series of parallel restricted zones in the mattress border. The stitching heads and the feed rollers are actuated by a belt 48 extending about a pulley 50 which is driven by a belt 51 rotated by a motor 52.

It will be noted that through the foregoing construction, the casing material is folded about the wall padding material, and that the marginal edges of the casing material are folded outwardly upon itself to reinforce the edges of the casing material. An examination of Figures 5 and 6 of the drawings will show that the lines of stitching 53 extend through the folded marginal edges 33 and in preferred form extend beyond the outer-most rows of stitching 53 to form flaps 54. These flaps 54 may be of benefit in the manufacture of the mattress, as in some forms of mattress construction it is desired to extend the inner lining 55 covering the springs 56 out over the opposed edges 57 of the mattress border to attach the lining 55 marginally to the attaching flaps 54. When the border has been attached to the inner lining 55 in this way, padding 59 is placed to overlie each of the linings 55 and an outer covering member 60 overlies the padding 59 to be marginally connected by stitching 61 to the border covering member 41.

Thus not only do the folded edges 33 act to provide a reinforced edge through which the rows of stitching 53 may extend, but also these folded

edges 33 may form attaching flaps to secure the mattress border to the mattress.

In Figures 8 and 9 of the drawings, I disclose a slightly modified form of construction in which the mattress border is stitched along curved or wavy lines to provide a decorative design in the stitching along the border. Two units of the machine are shown side by side in Figure 9 of the drawings. The construction of the folding machines for the border are, however, identical to those which have been previously described. A frame 62 supports a pair of spaced U-shaped frame members 63 for each of the border forming units, which frame members are identical to the frame members 24 and 25. A guide 64 identical to the guide 15 is suspended from the frame member 63 and a cooperating trough-shaped guide 65 supported by the frame members 63 acts to fold the casing sheets 66 about the padding strip 67 which is unrolled from the roll 69 supported by a suitable bracket 70. After the casing sheet 66 has been folded about each of the padding strips 67, the enclosed padding is guided by the rollers 71 upwardly over the guide table 72. The border covering strip 73 is drawn from a roll 74 rotatably mounted upon a bracket 75 and overlies the enclosed padding in a manner which has been previously described. The guide 76 directs the assembled unit upwardly beneath the stitching unit 77 which acts to sew a pattern upon the border. Feed rolls 78 draw the padding past the stitching heads 77 and from the various rolls.

It will be seen that the machines illustrated in Figures 8 and 9 are very similar to that previously described with the exception that the mattress border after it has been assembled is carried vertically past the stitching head 77 to permit the decorative border to be formed thereby. The border formed is illustrated in Figure 10 of the drawings and is virtually identical with the border illustrated in Figure 5 with the exception that more lines of stitching 80 are often formed on the machine illustrated in Figures 8 and 9.

It will be noted that the marginal edges 81 of the casing 66 are folded outwardly to form a reinforced marginal edge, but in the form illustrated in Figure 10, the edges 81 are not folded back. Whether or not the binding edge is formed depends upon the width of casing material used, as if a wider casing material is used, the marginal edges of the casing will fall back farther than they will when other material is used. The unfolded edge construction shown in Figure 10 is not peculiar to the particular stitching shown in this figure, but could be used as in Figure 5. Similarly, the border of Figure 10 could have folded edges.

In Figure 11 I disclose an arrangement of guides which will permit the casing 82 to be folded with its edges in overlapping relation. The guiding trough 83 (similar to the guiding trough 15) is provided with one inwardly projecting edge 84 which extends laterally beyond the center. A second inwardly projecting edge 85, rather than being formed in opposed relation to the edge 84, is above the level thereof, and the marginal edge of the edge 85 is in overlapping relation with the edge 84.

An inverted U-shaped bracket 86 similar to the frame member 25 is provided with parallel supporting legs 87 and a connecting cross member 89. A parallel cross member 90 forms a

support to which the trough 83 is attached by bolts 91.

An inner forming trough 92 is supported within the trough 83 in spaced relation thereto. The trough 92 is suspended from the cross frame member 89 by means of a rod or strip 93. The rod 93 extends downwardly from the cross member 89, transversely between the overlapping edges 84 and 85, and downwardly into engagement with the cross connecting member 94 on the inner trough 92. In this construction (as in the previously described construction) the covering strip 95 may join the assembly from the under side, to be on the side of the border opposite the side containing the seam. The assembly is stitched as at 98.

The manner in which the border of Figure 12 can be secured in a mattress is shown in Figure 13. The folded marginal edges 96 and 97 are attached to the marginal edges of the upper and lower linings 99 and 100 which extend over and under, respectively, the spring unit 101. The outer covering strip 95 is marginally secured to the top covering 102 and the bottom covering 103, respectively. Padding 104 extends between the linings 99 and 100 and the adjacent coverings 102 and 103, and the edges of the borders may overlie the marginal edges of the spring unit 101, as shown. The filling within the border is designated by numeral 104.

In accordance with the patent statutes, I have described the principles of construction and operation of my mattress border forming device; and while I have endeavored to set forth the best embodiments thereof, I desire to have it understood that these are only illustrative of ways of carrying out my invention, and that obvious changes may be made within the scope of the following claims without departing from the spirit of my invention.

I claim:

1. In a device for forming mattress borders, the combination of folding means for the casing material thereof, comprising a pair of vertically spaced guide plates of substantially like dimensions adapted to receive the casing material therebetween, oppositely disposed folding horns adjacent the opposite edge portions of said plates and extending inwardly to positions closely adjacent each other at the delivery end of the horns and providing channels for receiving the respective edge portions of said casing material, means for supplying a padding material between said horns, and means for drawing the casing material between said plates and through said horns and channels for folding the opposite edge portions of the casing material inwardly to positions adjacent each other and in a manner to surround said padding material.

2. In a device for forming mattress borders, the combination of folding means for the casing material thereof comprising a pair of vertically spaced coextensive guide plates adapted to receive the casing material therebetween, oppositely disposed folding horns adjacent the opposite edge portions of said plates and extending inwardly to positions adjacent each other and adjacent the central longitudinal portion of the plates, said horns providing channels for receiving the respective edge portions of said casing material, means for supplying a padding material between said horns immediately above one of said guide plates, and means for drawing the casing material between said plates and through said horns and channels for folding the opposite edge por-

tions of the casing material inwardly to positions adjacent each other and in a manner to surround said padding material.

3. In a device for forming mattress borders, the combination of folding means for the casing material thereof, comprising a pair of vertically spaced guide plates of substantially uniform dimensions adapted to receive the casing material therebetween, oppositely disposed folding horns adjacent the opposite edge portions of the plates and extending inwardly to positions adjacent each other and providing channels for receiving the respective edge portions of said casing material, means for supplying a padding material between said horns immediately above the uppermost of said guide plates, and means for drawing the padding material between said horns and the casing material between said plates and through said horns and channels for folding the opposite edge portions of the casing material inwardly to positions adjacent each other for surrounding said padding material.

4. In a device for forming mattress borders, a guide, means supplying a padding strip thereto, a second guide spaced below said first guide, means for supplying a casing strip between said guides, cooperating means on said first and second guides to fold the edges of said casing strip into overlapping relation over said padding, said co-operating means holding the marginal edges of said

20 casing folded outwardly toward the edges of said padding, means supplying a covering strip to said encased padding strip, and means for drawing said covering strip, padding, and casing strip past said guides.

5. In a device for forming mattress borders, a guide, means supplying a padding strip thereto, a second guide spaced from said first guide, cooperating means on said first and second guides 15 to fold said casing strip over said padding, said cooperating means holding the marginal edges of said casing folded outwardly toward the edges of said padding, means supplying a covering strip to overlie the surface of said casing opposite said folded edges, and means securing said casing, padding, and covering strip together.

6. In a device for forming mattress borders, a guide, means supplying a padding strip thereto, a second guide spaced from said first guide, means supplying a casing strip between said guides, means on said second guide curved to fold said casing strip over said padding, said casing strip being wider than said second guide to provide unfolded marginal portions above said second guide, means supplying a strip of covering material to the surface of said casing opposite said folded marginal edges, and means securing said casing strip, padding, and covering strip together.
